CLAIM

The ornamental design for an electronic device, as shown and described.

DESCRIPTION

The file of this patent contains at least one drawing/photograph executed in color. Copies of this patent with color

drawing(s)/photograph(s) will be provided by the Office upon request and payment of the necessary fee.

This application incorporates by reference in its entirety Design application Ser. No. 29/852,194, filed Sep. 4, 2022. FIG. 1 is a front right side perspective view of the first embodiment of an electronic device showing the claimed design;

FIG. 2 is a front left side perspective view thereof;

FIG. 3 is a rear right side perspective view thereof;

FIG. 4 is a rear left side perspective view thereof;

FIG. 5 is a front elevation view thereof;

FIG. 6 is a rear elevation view thereof;

FIG. 7 is a left side elevation view thereof;

FIG. 8 is right side elevation view thereof;

FIG. 9 is a top plan view thereof;

FIG. 10 is a bottom plan view thereof;

FIG. 11 is a front right side perspective view of the second embodiment of an electronic device showing the claimed design;

FIG. 12 is a front left side perspective view thereof;

FIG. 13 is a rear right side perspective view thereof;

FIG. 14 is a rear left side perspective view thereof;

FIG. 15 is a front elevation view thereof;

FIG. 16 is a rear elevation view thereof;

FIG. 17 is a left side elevation view thereof;

FIG. 18 is right side elevation view thereof;

FIG. 19 is a top plan view thereof; and,

FIG. 20 is a bottom plan view thereof.

The dot-dash broken lines in the figures and the areas within the dot-dash broken lines show portions of the electronic device that form no part of the claimed design.
